(57) **CLAIM**

The ornamental design for a surgical instrument, as shown and described.

DESCRIPTION

FIG. 1 is a right side view of a surgical instrument, showing my design;

FIG. 2 is a left side view thereof;

FIG. 3 is a top view thereof;

FIG. 4 is a bottom view thereof;

FIG. 5 is a front view thereof;

FIG. 6 is a rear view thereof;

FIG. 7 is a top-rear-right perspective view thereof;

FIG. 8 is a rear-right perspective view thereof; and,

FIG. 9 is a rear-right perspective view thereof with the lever in an alternate position.

The broken lines in the figures depict portions of the surgical instrument which form no part of the claimed design.
